CLAIM

We claim the ornamental design for an information handling system housing, as shown and described.

DESCRIPTION

FIG. 1 is a front perspective view of the information handling system housing in a closed position comprising the present invention;

FIG. 2 is a front view thereof;

FIG. 3 is a back side view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof in an open position;

FIG. 9 is front perspective view of a docking station on which the information handling system housing rests; and,

FIG. 10 is a rear perspective view thereof in an open position resting on the docking station.

Broken lines shown in the drawings illustrate portions of the information handling system housing, and form no part of the claimed design.
